(57) **CLAIM**

The ornamental design for a computer port receiver as shown and described.

DESCRIPTION

FIG. 1 is a front view of a computer port receiver showing my new design;

FIG. 2 is a rear view of the computer port receiver;

FIG. 3 is a top front side perspective view of the computer port receiver;

FIG. 4 is a right side view of the computer port receiver;

FIG. 5 is a left side view of the computer port receiver;

FIG. 6 is a top view of the computer port receiver; and,

FIG. 7 is a bottom view of the computer port receiver.
